COMBINATION CONDIMENTS HOLDER

John Flask and Elton Geer, Warren, Ohio

Application November 4, 1937, Serial No. 172,801

3 Claims. (Cl. 65—45)

This invention appertains to new and useful improvements in holders for condiments and more particularly to a combination salt and pepper shaker.

5 The principal object of the present invention is to provide a combination condiment holder wherein the adjustable cap is normally set to permit the dispensing of one condiment and wherein the cap can be moved conveniently to 10 permit the dispensing of a second condiment.

Another important object of the invention is 15 to provide a combination condiment holder of the character stated which can be readily refilled whenever desired in a convenient and expeditious manner.

Other important objects and advantages of the invention will become apparent to the reader of the following specification.

In the drawings:—

20 Figure 1 represents a vertical sectional view through the holder.

Figure 2 is a fragmentary detailed sectional view taken substantially on the line 2—2 of Figure 1.

25 Figure 3 is a fragmentary side elevational view of the upper portion of the holder.

Figure 4 is a fragmentary vertical sectional view through the holder with the cap in laterally disposed position.

30 Figure 5 is a horizontal sectional view taken substantially on the line 5—5 of Figure 1.

Figure 6 is a perspective view of the cap.

Referring to the drawings wherein like numerals designate like parts, it can be seen that the 35 holder consists of the base 5 and the upstanding wall structure 6 thereon. The interior of this wall structure 6 is provided with the vertical partition 7 which divides the interior of the container into the salt and pepper cells 8—9.

40 The partition 7 is provided with the thickened head portion 10 having a dove-tail shaped channel 11 therein extending its entire length and opening through the side wall 6 of the container at the upper end thereof.

45 The upper portion of the container wall 6 is reduced to define a shoulder 12 upon which the lower edge of the hemispherical-shaped cap 13 can rest. The cap 13 is rotatable and has the handle or knob 14 projecting outwardly thereof.

50 Numeral 15 represents the fixed cap and extending downwardly on a diametrical line from the inside of the cap 15 are the plates 16—17 which at their intermediate portions are laterally formed to permit the pin 18 to be vertically disposed and slidable therebetween. The upper

end of this pin 18 is provided with a head 19 which rests upon the cap 13 while the lower end is also provided with a head 20. The lower portions of the plates 16—17 are flared outwardly as at 21 to engage snugly into the dove-tail channel 11. This flaring 21 defines shoulders 22 between which and the head 20 a coiled compressible spring 23 is located to maintain the pin 18 in a downwardly urged position, maintaining the cap 13 snugly engaged against the top side of the 10 cap 15.

The plates 16 and 17 are fixed to the inner side of the cap 15 by lugs 24 and rivets 25.

As is shown in Figure 5, the cap 13 is provided with the inwardly disposed lug 26 with which the 15 outwardly disposed lug 27 on the inner cap 15 normally abuts, this lug 27 being located in the groove 28 which is circumferentially disposed in the fixed cap 15.

The fixed cap 15 has the eye 29 protruding outwardly therefrom and between this and the eye 30 on the rotatable cap 13 is the coiled extensible spring 31. These eyes 30 and 29 as well as the spring 31 are located within the confines of the circumferential groove 28 of the fixed cap 15. 20 25

The rotatable cap 13 is provided with the triangular-shaped opening 32 which is normally registered with the perforations 33 of the fixed cap 15. However, by rotating the cap, the cap 13 can be brought to register with the smaller 30 35 openings 34 so that pepper can be dispensed.

Obviously, by lifting upwardly on the handle 14 so as to lift the cap 13 above the cap 15, the cap 15 along with the cap 13 can be slid laterally so that the assembly is shifted to one 35 side as shown in Figure 4, thus permitting the holder to be refilled.

While the foregoing specification sets forth the invention in specific terms, it is to be understood that numerous changes in the shape, size 40 and materials may be resorted to without departing from the spirit and scope of the invention as claimed hereinafter.

Having described the invention, what is claimed as new is:—

1. A condiment holder comprising a container, a partition in the container having a groove in its upper end which passes through the wall of the container, a cap seated on the upper end of the container, a partition in the cap having its 50 lower end extended and engaging the groove, said cap being provided with an area of perforations at each side of the partition therein, a second cap fitting over the first cap and normally having its lower end fitting over the upper end of the 55

5 container, a pivot pin connecting the central portion of the two caps together, a spring carried by the pin for permitting the second cap to be raised relative to the first cap to permit its lower end to be raised above the upper end of the container, after which the two caps can be moved laterally with the lower end of the partition of the first cap sliding in the groove of the partition of the container, said second cap having 10 an opening therein registerable with one or the other of the perforated areas of the first cap.

15 2. A condiment holder comprising a container, a partition vertically arranged in the container and having a dove-tailed groove in its upper end, the ends of the groove passing through the walls 20 of the container, a cap fitted on the upper end of the container, a partition in the cap having its lower end of dove-tail shape to slidably engage the groove, said cap being provided with an area of perforations at each side of the partition therein, a second cap fitting over the first cap and normally having its lower end fitting over the upper end of the container, a pivot pin passing through the central portion of the two caps and through the partitions of the first cap, a spring encircling a part of the pin and engaging 25 a projection on the pin and the projection on the partition for normally holding the pin in lowered position, the second cap having an opening therein registerable with one or the other of the perforated areas, said first cap having the circumferentially extending groove therein, a spring located in part of the groove and having one end connected to the first cap and the other end to the second cap, and projections carried by the two caps and located in the grooves for limiting 30 rotary movement of the second cap on the first cap.

3. A condiment holder comprising a container, a partition vertically arranged in the container and having a dove-tailed groove in its upper end, the ends of the groove passing through the walls of the container, a cap fitted on the upper end 5 of the container, a partition in the cap having its lower end of dove-tail shape to slidably engage the groove, said cap being provided with an area of perforations at each side of partition therein, a second cap fitting over the first cap and normally having its lower end fitting over the upper end of the container, a pivot pin passing through the central portion of the two caps and through the partitions of the first cap, a spring encircling a part of the pin and engaging 15 a projection on the pin and the projection on the partition for normally holding the pin in lowered position, the second cap having an opening therein registerable with one or the other of the perforated areas, said first cap having the circumferentially extending groove therein, a spring located in part of the groove and having one end connected to the first cap and the other end to the second cap, and projections carried by the two caps and located in the grooves for limiting 20 25 rotary movement of the second cap on the first cap.
